UNITED STATES PATENT OFFICE.

JOHN W. MORGAN, OF WASHINGTON, DISTRICT OF COLUMBIA.

PAPER BOX.

SPECIFICATION forming part of Letters Patent No. 393,655, dated November 27, 1888.

Application filed March 29, 1887. Serial No. 232,829. (No model.)

To all whom it may concern:

Be it known that I, JOHN W. MORGAN, of Washington, in the District of Columbia, have invented certain new and useful Improvements 5 in Paper Boxes; and I do hereby declare the following to be a full, clear, and exact description of the invention, such as will enable others skilled in the art to which it appertains to make and use the same.

10 This invention relates to certain new and useful improvements in the attachment to pasteboard or paper boxes of the carrying bails or cords; and it consists, substantially, in such features of improvement as will hereinafter be more particularly described or pointed out.

In pasteboard or paper boxes, as constructed in many instances heretofore, the attachment of the carrying bail or cord is of such a weak 20 nature as that the weight of the boxes when filled very frequently proves too great to permit of said box being carried by the cord or bail in the manner intended, the bail many times breaking away from the box and causing considerable inconvenience to the persons carrying the same.

The defect above noted has resulted in my devising the present invention, wherein I attach or secure to the under side of one of the 30 meeting or connecting flaps or edges of the box a longitudinal strip of stiff paper or pasteboard, adjacent to the inner edge of which I form in said connecting flap or edge of the box suitable openings for the passage of the ends 35 of the carrying cord or bail. The ends of said carrying cord or bail I paste or otherwise attach to the under side of the upper connecting flap or edge of the box, and the two flaps are pasted together, the said upper flap being 40 brought down upon the lower flap, and thus will the two flaps of the box be firmly secured together and the two ends of the carrying bail or cord firmly held between them. The said carrying cord or bail passes beneath the longitudinal 45 reinforced strip of stiff paper or pasteboard, and is pasted thereto by any suitable adhesive mixture. In this way the weight of the box will be sustained in a much better manner than in many instances heretofore, 50 and by virtue of the double security thus provided for the carrying cord or bail the same is less liable to break away or become discon-

nected from the box, all as will more fully hereinafter appear when taken in connection with the accompanying drawings, wherein— 55

Figure 1 represents a longitudinal sectional view of a paper or pasteboard box, the same indicating the manner in which the two connecting flaps are united as well as the manner of attachment thereto of the carrying cord or 60 bail. Fig. 2 is a transverse sectional view taken on the line *x x*.

Reference being had to the several parts by the letters marked thereon, A represents a paper or pasteboard box, of any preferred construction or form, having its connecting edges or flaps *a* and *b* overlapping each other, as shown in the drawings, the same being united by any suitable gum or adhesive mixture, the upper one of said flaps being formed with the 70 openings *c c* for the passage therethrough of the ends of the carrying cord or bail. These ends of the said carrying cord or bail are firmly cemented or glued to the lower surface of the upper flap, *b*, of the box before the two 75 flaps are united together, and then when an adhesive mixture is applied to the upper surface of the lower flap, *a*, and the upper flap is brought down upon the lower flap the ends of the cord will become firmly secured between the two flaps in an obvious manner. 80

Secured to the under side of the upper flap of the box alongside the openings is a longitudinal strengthening or re-enforce strip, D, of stiff paper or pasteboard, and that portion 85 of the ends of the carrying cord or bail E passing over said strip are cemented thereto in like manner as the extremities thereof are secured between the two flaps.

From the foregoing description it will be 90 seen that by attaching the carrying cord or bail to the box in the manner described the latter can be used for a much greater length of time than in many instances heretofore, and that the same is not as apt to become torn or 95 broken from use in carrying. It will also be seen that the attachment or connection of the carrying cord or bail is rendered very secure and less liable to become broken, both of which are a very valuable desideratum in this class 100 of inventions wherein the purpose is to provide a paper or pasteboard box which can be used for an unlimited number of times.

Having thus described my invention, what I

claim as new, and desire to secure by Letters Patent, is—

In a paper or pasteboard box, the combination, with the box having overlapping meeting edges or flaps united by an adhesive compound, one of said flaps being provided with openings for the passage of the carrying cord or bail, of the longitudinal strengthening or re-enforce strip secured to the under side of said flap adjacent to its openings, and the carrying cord or bail having its ends passing

through said openings and secured to said strip and between the two flaps of the box, substantially in the manner shown or described.

In testimony whereof I have hereunto subscribed my name in the presence of two subscribing witnesses.

JOHN W. MORGAN.

Witnesses:

S. A. TERRY,
G. P. RENNEKER.
